(57) **CLAIM**

The ornamental design for a plant binding clip, as shown and described.

DESCRIPTION

FIG. 1 is a perspective view of a plant binding clip showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of a plant binding clip, shown with environment.

The broken line showing of the plant binding clip is for the purpose of illustrating portions of the article and forms no part of the claimed design. The broken line showing of environment in FIG. 8 forms no part of the claimed design.

1 Claim, 6 Drawing Sheets
